UNITED STATES PATENT OFFICE.

JAMES BROOKS CLOSE, OF SITTINGBOURNE, ENGLAND.

PROJECTILE.

1,301,907.

Specification of Letters Patent. Patented Apr. 29, 1919.

Application filed November 3, 1917. Serial No. 200,165.

To all whom it may concern:

Be it known that I, JAMES BROOKS CLOSE, a subject of the King of England, residing at Sittingbourne, Kent, in England, have invented certain new and useful Improvements in Projectiles, of which the following is a specification.

This invention relates to projectiles more particularly bombs or grenades and of the type adapted to be fired from rifles or other ordnance and has for its object to effect certain improvements in the fuse, in the body of the projectile and in the tail rod or like device with which these projectiles are sometimes provided.

It has been found that in existing constructions of rifle grenade or projectiles of that type there is a tendency for them to misfire or fail to go off if they strike the ground at an acute angle and moreover in soft ground such projectiles have a tendency for the explosion to occur only after the projectile has entered the ground to an extent which causes the violence of the explosion to be largely nullified. Further in the case of a rifle grenade the existing arrangements for limiting the extent to which the tail rod can be inserted into the barrel of the rifle in order to modify the range are unsatisfactory and are not easy to manipulate. Some modification in the construction of the body is also desirable with the view to effect better fragmentation. The present improvements obviate these several disadvantages and enable a simple, cheap and effective projectile to be produced.

According to this invention the detonator which is preferably contained in a blank service cartridge case is disposed in the casing or body of the projectile with the cap of the cartridge directed forwardly and adjacent to this cap is arranged a sleeve or tube which is fixed in some convenient manner to the casing. A striker member is so mounted in the fixed sleeve that it can slide therein toward the cap and a member is provided which projects forwardly from the projectile this member being so constructed and arranged that on impact even with soft ground it will impart sliding movement to the striker and cause it to detonate the cap. A plurality of locking members are carried loosely in radial openings formed through the fixed sleeve each locking member being of such shape and dimensions that as long as it is prevented from projecting outwardly

from the sleeve it will project within the sleeve and engage the striker member and thus hold it in a position of safety so that it cannot move toward the cap. A loose sleeve 60 or collar is mounted on the fixed sleeve so that it can slide rearwardly thereon by reason of its inertia when the projectile is discharged from the gun. When in its initial position the loose sleeve closes the outer 65 ends of the openings in the fixed sleeve in which lie the locking members and the loose sleeve thus maintains the locking members in engagement with the striker member until this sleeve is set back on discharge. The 70 locking members are then free to move outwardly through and out of the openings in which they lie and the striker member is thus released and on impact will be impelled by the forwardly projecting member against 75 the cap and the charge will be thereby detonated. A shearing wire passes through the fixed sleeve and the striker member and holds the latter after it has been released by the locking members until impact occurs 80 when the wire will be sheared as the striker is forced toward the cap. Means are provided for preventing movement of the loose sleeve in the rearward direction so as to release the locking members and free the 85 striker until the projectile is discharged. Conveniently the same shearing wire is employed for this purpose as is used to hold the striker member in position in the fixed sleeve after the locking members have been 90 allowed to move clear of the striker. One and the same shearing wire is then passed through the loose sleeve, the fixed sleeve and the striker member and the end portions of this wire will then be sheared when the loose 95 sleeve sets back on discharge while the intermediate part will be sheared as the striker is moved rearwardly on impact.

Where the projectile is intended to be used as a grenade which is to be fired from a rifle a tail rod of the usual type is attached to the rear end of the casing. This tail rod is adapted to fit the barrel of the rifle and has a series of annular grooves or notches formed in it at convenient distances apart 100 along its length. A wire of suitable dimensions is coiled once around the rod with the ends of the wire crossing each other and projecting so that the wire forms a spring member which when the ends are pressed together can be disengaged from one notch 105 and moved along the rod and engaged with

another notch. The wire constitutes such a projection on the rod as will prevent the latter from entering the barrel of the rifle beyond the point where the spring wire is positioned. By this means the range of the grenade when thrown from the rifle can be varied. Other forms of spring device can be employed and operated in a similar manner for this purpose in conjunction with the notches in the tail rod.

In order that the body of the projectile may break up into suitable fragments when the charge within it is exploded the segmentation of the casing is carried out on the inside instead of on the outside as is more usual in projectiles of the grenade or bomb type. Thus the exterior of the casing is formed smooth while the inner surface of the wall of the chamber which contains the explosive charge is divided up by suitable indentations or grooves which cross each other and are so disposed that when the charge is exploded the body of the projectile will readily break up into pieces of a desirable size.

25 The accompanying drawings illustrate by way of example two constructions of projectile according to this invention. In these drawings,

30 Figure 1 is an elevation of the improved projectile in one form in which it may be constructed for use as a grenade adapted to be fired from a rifle.

Fig. 2 is a longitudinal sectional elevation of the projectile shown in Fig. 1, the fuse being illustrated with the parts in the positions occupied by them when the fuse is in a state of safety.

Fig. 3 is a similar view showing the positions of the parts of the fuse immediately 40 after the projectile has been discharged and while it is in flight.

Fig. 4 is again a similar view illustrative of the positions assumed by the parts of the fuse when the charge is about to be detonated 45 on impact of the projectile.

Fig. 5 is a plan of the spring device which is mounted on the tail rod of the projectile for the purpose of varying the range when used as a rifle grenade.

50 Fig. 6 is a longitudinal sectional elevation showing a modification in the construction of the fuse.

Like letters indicate like parts throughout the drawings.

55 When constructed as shown in the drawings the projectile comprises a cylindrical body or casing A the rear end of which is tapered. This body contains the explosive charge and while the exterior is smooth the interior is provided with grooves A' formed in the thickness of the metal which cross each other as shown. The wall of the body is thus reduced in thickness in such places that when the charge explodes the body will 60 tend to break into pieces along the lines of

the grooves A' and in a more effective manner than if similar grooves are formed in the exterior of the wall of the body.

In the forward end of the casing A is formed a central hole of such diameter as to 70 permit of the explosive charge being filled into the casing through this hole. The hole is also of such diameter as to allow an ordinary small arm cartridge case to be inserted in the hole this cartridge case being provided 75 with the usual cap and containing a detonator of suitable type. The rim B' of the cartridge rests on an inwardly directed flange A² formed at the inner end of the hole through the end of the casing A so that the 80 cap B² of the cartridge faces the forward end of the projectile. Conveniently the cartridge is inclosed in a sheet metal tube or gaine C the inner end of which is closed while the outer end is flanged outwardly to 85 rest on the flange A² beneath the rim B' of the cartridge. The hole in the forward end of the projectile is screw-threaded to receive the correspondingly screw-threaded end of a sleeve or tube D. The interior of 90 this sleeve is cylindrical throughout while the exterior is cylindrical throughout the greater part of its length but toward the rear end the sleeve is slightly enlarged by a conical portion D'. When the sleeve D is 95 screwed into the end of the casing A the rim B' of the cartridge and the flange of the gaine are firmly held between the end of the sleeve D and the flange A². Toward the forward end of the sleeve there are formed 100 through its wall a series of circular radially arranged passages D² each of which is adapted to contain a ball or other locking member E. Each of these balls is of such dimensions that its diameter is greater than 105 the thickness of the wall of the sleeve D and preferably somewhat less than twice the thickness of this wall. Consequently each ball while it lies in its passage D² must project to some extent either into the interior 110 of the sleeve D or on its exterior.

Within the sleeve D lies a striker member which comprises a body portion F which is cylindrical and a free sliding fit within the tube D, and a rearwardly directed pin or rod 115 F' on the end of which is mounted a needle or nipple F². The nipple F² lies opposite to the cap B² and is adapted to detonate this cap when the striker member is forced inward. In the body portion F of the striker member is formed an annular groove F³ of such depth and width that those portions of the locking balls E which project into the interior of the sleeve D can engage the groove F³ and hold the striker rigidly in the 120 sleeve D. Thus until the balls E are disengaged from the groove F³ the striker cannot be moved rearwardly so as to detonate the cap B² and explode the charge which is disposed in the body or casing A around the 130

gaine C. From the forward end of the body portion F of the striker member projects a rod G which carries on its end a mushroom-shaped disk G' the diameter of which is preferably approximately equal to or slightly greater than the diameter of the cylindrical part of the casing A of the projectile. The rod G may be formed separate from the striker member but preferably as shown in the drawings it is integral therewith the mushroom head G' being riveted or otherwise attached to the end of the rod G.

On the exterior of the fixed sleeve D is mounted a loose sleeve or collar H which when freed is adapted to slide rearwardly or set back on the sleeve D by reason of its inertia when the projectile is discharged. The sleeve H is of such length that when in its forward position it will cover the openings D² in the fixed sleeve D and maintain the locking balls E in engagement with the groove F³ in the striker member F. When, however, the loose sleeve H sets back on discharge of the projectile and assumes the position shown in Fig. 3 the holes D² will be uncovered so that the locking balls E are free to escape outwardly through the openings D². The striker member is thus released and when the mushroom head G' strikes the ground or any object the striker will be impelled against the cap B² and the charge will be detonated. When the sleeve H sets back on discharge of the projectile the rearward end of this sleeve will be forced against the conical portion D' of the fixed sleeve D and the loose sleeve will consequently jam in this position and be held so that it will not tend to rebound or set forward again and once more cover the holes D² and prevent the free exit of the balls E.

It is necessary to provide some means for holding the striker member F when it has been released by the outward movement of the balls E otherwise premature detonation would be liable to occur for instance as a result of the air pressure on the mushroom head G' while the projectile is in flight. It is also necessary to provide some means for preventing accidental rearward displacement of the loose sleeve H prior to the discharge of the projectile and after the usual safety pin has been withdrawn. The striker member is held in the desired manner by a shearing wire J which is passed right through the body F of the striker member, preferably at its forward portion, and through the walls of the fixed sleeve D at the opposite sides of the striker member. Conveniently this same shearing wire J is also employed to hold the loose sleeve H until the projectile is discharged the wire being extended and its ends carried through the loose sleeve H in the manner shown in Fig. 2. Thus one and the same shearing wire J serves the double purpose of holding the

loose sleeve H and also holding the striker member F. When the projectile is discharged the end portions J' of the wire J are sheared between the loose sleeve H and the fixed sleeve D as the loose sleeve sets back in the manner shown in Fig. 3. On impact when the mushroom head G' strikes an object the intermediate portion of the wire J is sheared between the striker member F and the fixed sleeve D in the manner shown in Fig. 4 and the striker nipple F² is forced against the cap B².

The fuse device is conveniently inclosed in an outer sheet metal casing K which is conveniently formed as a cylindrical tube one end of which is spun over or flanged inwardly as at K' this flange being adapted to be gripped between the rearward end of the conical portion D' of the fixed sleeve D and the flat face of the projectile body A around the opening into which the fixed sleeve D is screwed. A safety pin L of the usual type is passed through the casing K and through corresponding coincident holes formed in the loose sleeve H, in the fixed sleeve D, and in the body portion F of the striker member, the hole in the latter being shown at F⁴ in Figs. 3 and 4. The parts of the fuse are thus rigidly held by the safety pin L until the projectile is to be discharged.

When the improved projectile is to be used as a rifle grenade there is mounted on its rearward end a tail rod M. This may conveniently be screwed into the rear end of the body A and fixed by a nut N. The rod M is adapted to enter the barrel of the rifle and it is customary to vary the range in a rough and ready manner by varying the extent to which the rod M is inserted in the rifle barrel. In order that this may be done in a simple and convenient manner and with some approximation to accuracy there are formed in the rod M a series of annular grooves or recesses M' which are suitably spaced apart along the length of the rod. A wire O the diameter of which is such as to adapt it to fit into each of the grooves M' is bent into a circle with the ends O' of the wire crossed over each other in the manner shown in Fig. 5. The spring or loop ring thus formed by the main portion of the wire O has an internal diameter slightly less than the main portion of the rod M and approximately equal to the diameter of this rod at the bottom of a groove M'. Thus the spring ring device O can engage any one of the grooves M' and this device will then grip the rod M in such a manner that it cannot be readily displaced on the rod unless it is properly manipulated. The spring device constitutes such a projection on the rod M as will prevent the latter from entering the rifle barrel beyond the point where the spring device is set and comes against the muzzle of the rifle. By pressing together

- with the fingers the ends O' of the spring ring O this ring can be enlarged sufficiently to release it from engagement with one groove M' and allow the device to be moved 5 along the rod and into engagement with another groove M' . The grooves M' are preferably spaced apart along the rod M in positions which may be determined by experiment and will result in various ranges being 10 given to the grenade according to the position along the rod at which the spring stop device O may be fixed.
- It will seem that this device is simple and easy to manipulate and by reason of its 15 automatic grip on the rod M it is not likely to be readily lost or to slip off the rod. At the same time the device O forms an efficient stop for the purpose.
- When the projectile is to be discharged the 20 spring stop O is adjusted on the rod M so as to engage that groove M' which corresponds to the desired range. The safety pin L is then pulled out. The rod M is then inserted in the barrel of the rifle in the breech of 25 which is a blank service cartridge. On discharge the loose sleeve H sets back into the position shown in Fig. 3 the end portions J' of the wire J being sheared. The loose sleeve H then jams on the conical rear end 30 D' of the fixed sleeve D and is there held. While the projectile is in flight the balls E are thrown outwardly so as to release the striker member F . When the projectile strikes its objective the impact of the mushroom head G' even on soft ground will shear the intermediate portion of the wire J and force the striker into the position shown in 35 Fig. 4 when the cap B^2 will be detonated and the main charge exploded.
- 40 The mushroom head G' may be shaped otherwise than as more particularly described and illustrated in the drawings the shape being varied as found desirable so as to offer as little resistance as possible while 45 the projectile is in flight while being adapted to act in the desired manner on the striker when impact occurs.
- It is to be noted that in the construction 50 illustrated the arrangement is such that the parts of the projectile and fuse are simple to make and assemble. Conveniently the main explosive charge is filled into the body A through the opening in the forward end and the gaine C is then inserted, but the detonating cartridge B need not be placed in position 55 until the projectile is about to be required for use so that risk of accidental discharge is avoided. The fixed sleeve D and the parts carried thereby may also be maintained separate from the body A until the 60 projectile is likely to be employed. The assembling of the parts so as to be ready for use can be readily performed as it is merely necessary to slip into the gaine C the cartridge B containing the detonator. The 65

fixed sleeve D is then screwed into place and the projectile is ready for use.

Though a small arm cartridge case such as B is preferably intended to be employed as a container for the detonator some other arrangement of detonator may be used if desired with a cap so mounted that it will lie in the position occupied by the cap B^2 in the construction shown in the drawings.

In Fig. 5 is shown an alternative device 75 which may be employed for the purpose of holding the loose sleeve H in place of extending the ends of the shearing wire J through that sleeve. In this case one or more flat springs P are disposed in shallow longitudinal recesses formed in the exterior of the fixed sleeve D . The forward end of each spring lies beneath a collar Q which is mounted at the forward end of the fixed sleeve D and conveniently fixed thereon by 80 screws Q' each of which passes through the end of a spring P . The rearward end P' of each spring P is turned slightly outward so as to bear against the interior of and the end portion of the loose sleeve H and offer resistance to rearward movement of this sleeve. On discharge the loose sleeve H will set back over the ends P' of the springs P which will be compressed to allow of this and the sleeve H can thus move into its rearward position 95 and jam against the conical part D' of the fixed sleeve D . The ends P' of the springs will also by their outward pressure and engagement with the interior of the loose sleeve H tend to prevent rebound or forward movement of this sleeve.

Though as more particularly described above and illustrated in the drawings the improved projectile is especially intended for use as a rifle grenade or bomb it is to be 105 noted that it may be constructed for use as a projectile to be fired from a trench mortar or other gun or it may be otherwise employed for offensive purposes.

If desired the casing or body A of the 110 projectile may have an opening formed in its rear end this opening being closed by a suitable plug screwed into place. The filling of the explosive charge into the casing may then be effected through this opening 115 after the gaine C has been put in position. Where the projectile is intended to be used as a rifle grenade with a tail rod such as M the end of the latter can be screwed into the plug which closes the rear opening.

What I claim as my invention and desire to secure by Letters Patent is:—

1. In a projectile the combination of a casing containing an explosive charge, a detonator for this charge carried by the casing, 125 a sleeve fixed to the casing, a striker member mounted in the fixed sleeve so that it can slide therein toward the detonator, a member which projects forwardly from the projectile and is adapted on impact to act on 130

and impart sliding movement to the striker member, a plurality of locking members carried loosely in radial passages formed through the fixed sleeve each locking member being of such shape and dimensions that while the outer end of the radial passage in which it lies is closed the locking member will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the locking members in engagement with the striker member, a shearing wire which passes through the fixed sleeve and the striker member, and means for preventing such rearward movement of the loose sleeve as will release the locking members until the projectile is discharged as set forth.

2. In a projectile the combination of a casing containing an explosive charge, a detonator for this charge carried by the casing, a sleeve fixed to the casing, a striker member mounted in the fixed sleeve so that it can slide therein toward the detonator, a member which projects forwardly from the projectile and is adapted on impact to act on and impart sliding movement to the striker member, a plurality of locking members carried loosely in radial passages formed through the fixed sleeve each locking member being of such shape and dimensions that when in position in the passage its measurement in the radial direction with relation to the axis of the fixed sleeve exceeds the thickness of the wall of the fixed sleeve so that while the outer end of the radial passage in which it lies is closed the locking member will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the locking members in engagement with the striker member, a shearing wire which passes through the fixed sleeve and the striker member, and means for preventing such rearward movement of the loose sleeve as will release the locking members until the projectile is discharged as set forth.

3. In a projectile the combination of a casing containing an explosive charge, a detonator for this charge carried by the casing, 60 a sleeve fixed to the casing, a striker member mounted on the fixed sleeve so that it can slide therein toward the detonator, a member which projects forwardly from the projectile and is adapted on impact to act on 65 and impart sliding movement to the striker

member, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the striker member, a shearing wire which passes through the fixed sleeve and the striker member, and means for preventing such rearward movement of the loose sleeve as will release the balls until the projectile is discharged as set forth. 70 75 80 85

4. In a projectile the combination of a casing containing an explosive charge, a detonator for this charge carried by the casing, a sleeve fixed to the casing, a striker member mounted in the fixed sleeve so that it can slide therein toward the detonator, a member which projects forwardly from the projectile and is adapted on impact to act on and impart sliding movement to the striker member, a plurality of locking members carried loosely in radial passages formed through the fixed sleeve each locking member being of such shape and dimensions that while the outer end of the radial passage in which it lies is closed the locking member will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the locking members in engagement with the striker member, means by which the loose sleeve is prevented from setting forward again after discharge of the projectile, a shearing wire which passes through the fixed sleeve and the striker member, and means for preventing such rearward movement of the loose sleeve as will release the locking members until the projectile is discharged as set forth. 120

5. In a projectile the combination of a casing containing an explosive charge, a detonator for this charge carried by the casing, a sleeve fixed to the casing the exterior of which is formed cylindrical as to 125 its forward portion but provided with a conical portion at its rear end, a striker member mounted in the fixed sleeve so that it can slide therein toward the detonator, a member which projects forwardly from the 130

- projectile and is adapted on impact to act on and impart sliding movement to the striker member, a plurality of locking members carried loosely in radial passages 5 formed through the fixed sleeve each locking member being of such shape and dimensions that while the outer end of the radial passage in which it lies is closed the locking member will project within the 10 sleeve and engage the striker member, a loose sleeve mounted on the fixed sleeve so that it can slide rearwardly thereon by reason of its inertia when the projectile is discharged this loose sleeve when in its 15 initial position serving to close the outer ends of the radial passages in the fixed sleeve and maintain the locking members in engagement with the striker member but when the loose sleeve has set back and uncovered the ends of the radial passages and released the locking members the end of the 20 sleeve will engage and be held by the conical portion of the fixed sleeve, a shearing wire which passes through the fixed sleeve 25 and the striker member, and means for preventing such rearward movement of the loose sleeve as will release the locking members until the projectile is discharged as set forth.
- 30 6. In a projectile the combination of a casing containing an explosive charge, a detonator for this charge carried by the casing, a sleeve fixed to the casing, a striker member mounted in the fixed sleeve so that 35 it can slide therein toward the detonator, a member which projects forwardly from the projectile and is adapted on impact to act on and impart sliding movement to the striker member, a plurality of locking members 40 carried loosely in radial passages formed through the fixed sleeve each locking member being of such shape and dimensions that while the outer end of the radial passage in which it lies is closed the locking member will project within the sleeve 45 and engage the striker member, a loose sleeve mounted on the fixed sleeve so that it can slide rearwardly thereon by reason of its inertia when the projectile is discharged this 50 loose sleeve when in its initial position serving to close the outer ends of the radial passages in the fixed sleeve and maintain the locking members in engagement with the striker member, and a shearing wire 55 which passes through the loose sleeve, through the fixed sleeve and through the striker member as set forth.
- 60 7. In a projectile the combination of a casing containing an explosive charge, a detonator for this charge carried by the casing, a sleeve fixed to the casing, a striker member mounted in the fixed sleeve so that it can slide therein toward the detonator, a member which projects forwardly from the 65 projectile and is adapted on impact to act

on and impart sliding movement to the striker member, a plurality of locking members carried loosely in radial passages formed through the fixed sleeve each locking member being of such shape and dimensions that while the outer end of the radial passage in which it lies is closed the locking member will project within the sleeve and engage the striker member, a loose sleeve mounted on the fixed sleeve so 70 that it can slide rearwardly thereon by reason of its inertia when the projectile is discharged this loose sleeve when in its initial position serving to close the outer ends of the radial passages in the fixed sleeve and maintain the locking members in engagement with the striker member, and a wire passing through the loose sleeve through the fixed sleeve and through the 75 striker member and adapted to be sheared as to its end portions when the loose sleeve sets back on discharge and to be sheared as to its intermediate portion when the forwardly projecting member makes impact with an object and moves the striker member on to the detonator as set forth.

8. In a projectile the combination of a casing containing an explosive charge, a detonator for this charge carried by the casing, a sleeve fixed to the casing, a striker member mounted in the fixed sleeve so that 80 it can slide therein toward the detonator, a member formed integral with the striker member which projects forwardly from the nose of the projectile so that on impact the striker member will be caused to move toward the detonator, a plurality of locking members carried loosely in radial passages formed through the fixed sleeve each 85 locking member being of such shape and dimensions that while the outer end of the radial passage in which it lies is closed the locking member will project within the sleeve and engage the striker member, a loose sleeve mounted on the fixed sleeve so that 90 it can slide rearwardly thereon by reason of its inertia when the projectile is discharged this loose sleeve when in its initial position serving to close the outer ends of the radial passages in the fixed sleeve and 95 maintain the locking members in engagement with the striker member, a shearing wire which passes through the fixed sleeve and the striker member, and means for preventing such rearward movement of the loose sleeve as will release the locking members until the projectile is discharged as set forth.

100 9. In a projectile the combination of a casing containing an explosive charge, a detonator constituted by a blank small-arm cartridge carried by the casing with the cap end of the cartridge directed forwardly and the opposite end adjacent to the explosive charge, a sleeve fixed to the casing, a striker mem- 105

- ber mounted in the fixed sleeve so that it can slide therein toward the cap of the cartridge, a member which projects forwardly from the projectile and is adapted on impact 5 to act on and impart sliding movement to the striker member, a plurality of locking members carried loosely in radial passages formed through the fixed sleeve each locking member being of such shape and dimensions that while the outer end of the radial passage in which it lies is closed the locking member will project within the sleeve and engage the striker member, a loose sleeve mounted on the fixed sleeve so that it can 10 slide rearwardly thereon by reason of its inertia when the projectile is discharged this loose sleeve when in its initial position serving to close the outer ends of the radial passages in the fixed sleeve and maintain the locking members in engagement with the striker member, a shearing wire which passes through the fixed sleeve and the striker member, and means for preventing such rearward movement of the loose sleeve as 15 will release the locking members until the projectile is discharged as set forth.
10. In a projectile the combination of a casing containing an explosive charge, a detonator for this charge carried by the casing, a sleeve fixed to the casing, a striker member mounted on the fixed sleeve so that it can slide therein toward the detonator, a member which projects forwardly from the projectile and is adapted on impact to act 20 on and impart sliding movement to the striker member, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the striker member, and a wire passing through the loose sleeve through the fixed sleeve and through the striker member and adapted to be sheared as to its end portions when the loose sleeve sets back on discharge and to be sheared as to its intermediate portion when the forwardly projecting member makes impact with an object and moves the striker member on to the detonator as set forth.
11. In a projectile the combination of a casing containing an explosive charge, a detonator constituted by a blank small arm cartridge carried by the casing with the cap end of the cartridge directed forwardly and the opposite end adjacent to the explosive charge, a sleeve fixed to the casing the exterior of which is formed cylindrical as to its forward portion but provided with a conical portion at its rear end, a striker member mounted in the fixed sleeve so that it can slide therein toward the cap of the cartridge, a member which projects forwardly from the projectile and is adapted on impact to act on and impart sliding movement to the striker member, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the striker member but when the loose sleeve has set back and uncovered the ends of the radial passages and released the balls the end of the sleeve will engage and be held by the conical portion of the fixed sleeve,

shearing wire which passes through the fixed sleeve and the striker member, and means for preventing such rearward movement of the loose sleeve as will release the balls until the 5 projectile is discharged as set forth.

13. In a projectile the combination of a casing containing an explosive charge, a detonator constituted by a blank small-arm cartridge carried by the casing with the cap 10 end of the cartridge directed forwardly and the opposite end adjacent to the explosive charge, a sleeve fixed to the casing the exterior of which is formed cylindrical as to its forward portion but provided with a 15 conical portion at its rear end, a striker member mounted in the fixed sleeve so that it can slide therein toward the cap of the cartridge, a member which projects forwardly from the projectile and is adapted 20 on impact to act on and impart sliding movement to the striker member, a plurality of balls constituting locking members carried separately and loosely in radial passages formed through the fixed sleeve the 25 diameter of each ball exceeding the thickness of the wall of the fixed sleeve so that while the outer end of the radial passage in which it lies is closed a portion of the ball will project within the sleeve and engage 30 the striker member, a loose sleeve mounted on the fixed sleeve so that it can slide rearwardly thereon by reason of its inertia when the projectile is discharged this loose sleeve when in its initial position serving 35 to close the outer ends of the radial passages in the fixed sleeve and maintain the balls in engagement with the striker member but when the loose sleeve has set back and uncovered the ends of the radial 40 passages and released the balls the end of the sleeve will engage and be held by the conical portion of the fixed sleeve and a wire passing through the loose sleeve through the fixed sleeve and through the striker member 45 and adapted to be sheared as to its end portions when the loose sleeve sets back on discharge and to be sheared as to its intermediate portion when the forwardly projecting member makes impact with an object and moves the striker member on to the detonator 50 as set forth.

14. In a projectile the combination of a casing containing an explosive charge, a detonator for this charge carried in the casing, 55 a sleeve fixed to one end of the casing so as to project forwardly therefrom, a striker member mounted in the fixed sleeve so that it can slide therein toward the detonator, a member which projects forwardly beyond 60 the end of the fixed sleeve and is adapted on impact to act on and impart sliding movement to the striker member, a plurality of locking members carried loosely in radial passages formed through the fixed sleeve 65 each locking member being of such shape

and dimensions that while the outer end of the radial passage in which it lies is closed the locking member will project within the sleeve and engage the striker member, a loose sleeve mounted on the fixed 70 sleeve so that it can slide rearwardly thereon by reason of its inertia when the projectile is discharged this loose sleeve when in its initial position serving to close the outer ends of the radial passages in the fixed sleeve 75 and maintain the locking members in engagement with the striker member, a shearing wire which passes through the fixed sleeve and the striker member, and means for preventing such rearward movement of the loose sleeve as will release the locking 80 members until the projectile is discharged as set forth.

15. In a projectile the combination of a casing containing an explosive charge, a detonator for this charge carried in the casing, a sleeve fixed to one end of the casing so as to project forwardly therefrom, a striker member mounted in the fixed sleeve so that it can slide therein toward the detonator, a member which projects forwardly beyond the end of the fixed sleeve and is adapted on impact to act on and impart sliding movement to the striker member, a plurality of locking members carried loosely 90 in radial passages formed through the fixed sleeve each locking member being of such shape and dimensions that while the outer end of the radial passage in which it lies is closed the locking member will project 95 within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve 100 and maintain the locking members in engagement with the striker member, and a wire passing through the loose sleeve through the fixed sleeve and through the striker member and adapted to be sheared as to its end portions when the loose sleeve sets back on discharge and to be sheared as 105 to its intermediate portion when the forwardly projecting member makes impact with an object and moves the striker member on to the detonator 110 as set forth.

16. In a projectile the combination of a casing containing an explosive charge, a detonator for this charge carried in the casing, a sleeve fixed to one end of the casing so as to project forwardly therefrom, a striker member mounted in the fixed sleeve so that it can slide therein toward the detonator, a member which projects forwardly beyond 120 the end of the fixed sleeve and is adapted on impact to act on and impart sliding movement to the striker member, a plurality of balls constituting locking members car- 125

ried separately and loosely in radial passages formed through the fixed sleeve the diameter of each ball exceeding the thickness of the wall of the fixed sleeve so that 5 while the outer end of the radial passage in which it lies is closed a portion of the ball will project within the sleeve and engage the striker member, a loose sleeve mounted on the fixed sleeve so that it can slide rearwardly thereon by reason of its inertia when 10 the projectile is discharged this loose sleeve when in its initial position serving to close the outer ends of the radial passages in the fixed sleeve and maintain the balls in engagement with the striker member, means 15 by which the loose sleeve is prevented from setting forward again after discharge of the projectile, a shearing wire which passes through the fixed sleeve and the striker member, and means for preventing such rearward movement of the loose sleeve as will release the locking members until the projectile is discharged as set forth.

17. In a projectile the combination of a 20 casing containing an explosive charge, a detonator constituted by a blank small-arm cartridge carried in the casing with the cap end of the cartridge directed forwardly and the opposite end adjacent to the explosive charge, a sleeve fixed to one end of the casing so as to project forwardly therefrom the exterior of this sleeve being formed cylindrical as to its forward portion but provided with a conical portion at its rear end, a striker member mounted in the fixed sleeve so that it can slide therein toward the cap of the cartridge, a member which projects forwardly beyond the end of the fixed sleeve and is adapted on impact to act on 25 and impart sliding movement to the striker member, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the striker member, a 30 loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the groove in the striker member but when the loose sleeve has set back and uncovered the ends of the radial passages and released the balls the end of the sleeve will engage and be held by the 35 conical portion of the fixed sleeve, and a wire passing through the loose sleeve through the fixed sleeve and through the striker member and adapted to be sheared as to its end portions when the loose sleeve sets back on discharge and to be sheared as to its intermediate portion when the forwardly projecting member makes impact with an object and moves the striker member on to the detonator as set forth.

sets back on discharge and to be sheared as to its intermediate portion when the forwardly projecting member makes impact with an object and moves the striker member on to the detonator as set forth.

70

18. In a projectile the combination of a casing containing an explosive charge, a detonator constituted by a blank small-arm cartridge carried in the casing with the cap end of the cartridge directed forwardly and the opposite end adjacent to the explosive charge, a sleeve fixed to one end of the casing so as to project forwardly therefrom the exterior of this sleeve being formed cylindrical as to its forward portion but provided with a conical portion at its rear end,

75

a striker member mounted in the fixed sleeve so that it can slide therein toward the cap of the cartridge the striker member having an annular groove formed therein, a member formed integral with the striker member which projects forwardly beyond the end of the fixed sleeve so that on impact the striker member will be caused to move toward the

80

cap of the cartridge, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the annular groove in the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the groove in the striker member but when the loose sleeve has set back and uncovered the ends of the radial

85

passages and released the balls the end of the sleeve will engage and be held by the conical portion of the fixed sleeve, and a wire passing through the loose sleeve through the fixed sleeve and through the striker member and adapted to be sheared as to its end portions when the loose sleeve sets back on discharge and to be sheared as to its intermediate portion when the forwardly projecting member makes impact with an object and moves the striker member on to the detonator as set forth.

90

19. In a projectile the combination of a casing containing an explosive charge, a detonator constituted by a blank small-arm cartridge carried in the casing with the cap end of the cartridge directed forwardly and the opposite end adjacent to the explosive charge, a sleeve fixed to one end of the casing so as to project forwardly therefrom the exterior of this sleeve being formed cylindrical as to its forward portion but provided with a conical portion at its rear end,

95

a striker member mounted in the fixed sleeve so that it can slide therein toward the cap of the cartridge the striker member having an annular groove formed therein, a member formed integral with the striker member which projects forwardly beyond the end of the fixed sleeve so that on impact the striker member will be caused to move toward the

100

cap of the cartridge, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the annular groove in the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the groove in the striker member but when the loose sleeve has set back and uncovered the ends of the radial

105

passages and released the balls the end of the sleeve will engage and be held by the conical portion of the fixed sleeve, and a wire passing through the loose sleeve through the fixed sleeve and through the striker member and adapted to be sheared as to its end portions when the loose sleeve sets back on discharge and to be sheared as to its intermediate portion when the forwardly projecting member makes impact with an object and moves the striker member on to the detonator as set forth.

110

20. In a projectile the combination of a casing containing an explosive charge, a detonator constituted by a blank small-arm cartridge carried in the casing with the cap end of the cartridge directed forwardly and the opposite end adjacent to the explosive charge, a sleeve fixed to one end of the casing so as to project forwardly therefrom the exterior of this sleeve being formed cylindrical as to its forward portion but provided with a conical portion at its rear end,

115

a striker member mounted in the fixed sleeve so that it can slide therein toward the cap of the cartridge the striker member having an annular groove formed therein, a member formed integral with the striker member which projects forwardly beyond the end of the fixed sleeve so that on impact the striker member will be caused to move toward the

120

cap of the cartridge, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the annular groove in the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the groove in the striker member but when the loose sleeve has set back and uncovered the ends of the radial

125

passages and released the balls the end of the sleeve will engage and be held by the conical portion of the fixed sleeve, and a wire passing through the loose sleeve through the fixed sleeve and through the striker member and adapted to be sheared as to its end portions when the loose sleeve sets back on discharge and to be sheared as to its intermediate portion when the forwardly projecting member makes impact with an object and moves the striker member on to the detonator as set forth.

130

vided with a conical portion at its rear end, a striker member mounted in the fixed sleeve to that it can slide therein toward the cap of the cartridge, a member which projects forwardly beyond the end of the fixed sleeve and is adapted on impact to act on and impart sliding movement to the striker member, a plurality of balls constituting locking members carried separately and loosely in radial passages formed through the fixed sleeve the diameter of each ball exceeding the thickness of the wall of the fixed sleeve so that while the outer end of the radial passage in which it lies is closed a portion of the ball will project within the sleeve and engage the striker member, a loose sleeve mounted on the fixed sleeve so that it can slide rearwardly thereon by reason of its inertia when the projectile is discharged this loose sleeve when in its initial position serving to close the outer ends of the radial passages in the fixed sleeve and maintain the balls in engagement with the striker member but when the loose sleeve has set back and uncovered the ends of the radial passages

and released the balls the end of the sleeve will engage and be held by the conical portion of the fixed sleeve, a wire passing through the loose sleeve through the fixed sleeve and through the striker member and adapted to be sheared as to its end portions when the loose sleeve sets back on discharge and to be sheared as to its intermediate portion when the forwardly projecting member makes impact with an object and moves the striker member on to the detonator, and a cylindrical casing surrounding the loose sleeve and inclosing it and the fixed sleeve, this casing being fixed in relation to the fixed sleeve and having a withdrawable safety pin passed through it and through the movable and fixed parts within it as set forth.

In testimony whereof I have signed my name to this specification in the presence of two subscribing witnesses.

JAMES BROOKS CLOSE.
